UNITED STATES PATENT OFFICE.

HAMILTON ABERT, OF NEW YORK, N. Y.

PHOTOGRAPHIC-PRINTING DEVICE.

1,052,876.

Specification of Letters Patent. Patented Feb. 11, 1913.

Application filed February 23, 1912. Serial No. 679,221.

To all whom it may concern:

Be it known that I, HAMILTON ABERT, a citizen of the United States, residing in the city of New York, borough of Manhattan, 5 county and State of New York, have invented a certain new and useful Photographic-Printing Device, of which the following is a specification.

This invention is a photographic printing 10 device, and the object of the invention is to enable the printing operation to be carried out in such manner as to produce uniform prints, *i. e.*, prints which have been equally exposed at all parts thereof during the 15 printing operation.

With this object in view, the invention embodies a printing chamber, means for illuminating it, and means whereby the illuminating means is automatically lighted 20 after the introduction of the printing frame into the chamber and extinguished upon the withdrawal of the printing frame from said chamber.

In a preferred embodiment of the invention, the illuminating means is an incandescent lamp, in circuit with which is a switch positioned in the path of the printing frame and operable thereby, said printing frame operating to shut off the current, thereby 30 extinguishing the light, when starting to insert said printing frame into the chamber, and to switch on the current, thereby illuminating the lamp, upon the complete insertion of the printing frame into the chamber. 35 When the printing frame is withdrawn from the chamber, the reverse operation takes place; *i. e.*, upon starting to withdraw the printing frame from the chamber the light is extinguished and remains ext- 40 tinguished until after the printing frame is withdrawn from the chamber.

In the accompanying drawings, I have illustrated different practical embodiments of the invention, but the constructions dis- 45 closed therein are to be understood as illustrative, only, and not as defining the limits of the invention.

Figure 1 is a vertical section through a device embodying this invention adapted 50 for printing photographic negatives or the like. Fig. 2 is a horizontal section on the line 2—2 of Fig. 1, illustrating the operation of inserting a printing frame into the

chamber of the printing device. Fig. 3 is a vertical cross section on the line 3—3 of Fig. 1 looking in the direction of the arrow. Fig. 4 is a detail view in plan, partly in horizontal section, illustrating another embodiment of the switch mechanism by which the lamp is controlled automatically upon the insertion or withdrawal of a printing frame. Fig. 5 is a view, similar to Fig. 4, illustrating another embodiment of the switch mechanism.

The printing device embodies a casing A forming a printing chamber A', one practical embodiment of which casing will be hereinafter described in detail. The casing is of suitable dimensions to contain a printing frame of a predetermined size, and within the chamber A' is positioned means for illuminating said chamber. While various forms of illuminating means may be employed, I have shown said illuminating means in the form of an incandescent electric lamp B, the latter being positioned within the upper part of the chamber and at such a distance above the printing frame that there will be a proper dispersion of the rays of light. The incandescent lamp is shown as having a male threaded stem b which is adapted to be screwed into a female threaded socket b' of a fixture plate B'. Suitable provision is made for the electrical connection of the incandescent filament with a lighting circuit when the lamp is screwed into the socket, but as these details are well known to those skilled in the art, I have not considered it necessary to particularly describe or illustrate the electrical connections.

Casing A is provided at its lower part and in one of its walls with an opening a for the introduction or withdrawal of a printing frame C. Said printing frame is constructed in the ordinary or well known manner so that it will embody means for receiving a photographic negative, the sensitized paper upon which the print is to be made, and a suitable back for clamping the negative and the print paper in predetermined relation. As the printing frame is well known in the art, it has not been considered necessary to illustrate the same in detail. To adapt the printing frame for use with two forms of my new printing device, it becomes necessary to slightly modify or

alter the form of the printing frame, but in one embodiment of the invention, an ordinary printing frame without any modification or change in its structure is adapted for use in the printing device, as will herein-after appear.

The means for controlling the illuminating device is embodied, preferably, in the form of a switch mechanism positioned within the casing and in the path of the printing frame for co-operation therewith. Various forms of switch mechanisms may be used, three such forms being represented in Figs. 2, 4 and 5, respectively, of the drawings. Switch mechanism D represented in Fig. 2 embodies a spring composed, preferably, of plate metal, one end of which is fastened at d to the casing. Said switch spring is provided with a bend d' near its free end, said bend d' being normally in the path of a printing frame for contact with one edge thereof. The free end of switch spring D is adapted for engagement with a contact e, the latter being secured at e' so that the contact is normally in the path of the free end of the switch spring. The switch mechanism including the spring and the contact is electrically insulated from metallic contact with the casing by a layer of rubber, fiber, or other insulating material E.

The circuit connections for the lamp and the switch mechanism of Fig. 2 are as follows:—A feed wire f leads directly to the socket and the filament of the lamp; a return wire f' is connected with the screw or other device e' by which contact e is fixed to the insulating layer E and a branch conductor f² leads from the socket and lamp filament to the screw d by which the switch spring D is fixed to the insulation E. With the form of switch shown, frame C is provided in one of its side edges with a notch c, the latter occupying such position that upon the insertion of the printing frame to its operative position within the printing chamber, spring D will move in a direction to cause bend d' to enter said notch c, thus closing the electric circuit, and admitting current to lamp B.

The operation of the device as thus far described is as follows:—When the printing frame is not inserted into the casing, switch spring D is in electrical engagement with contact e, and current then flows through feed wire f, the lamp filament, branch conductor f², switch spring D, contact e, and return wire f'. Current is thus admitted to the lamp for the purpose of illuminating the printing chamber. When the printing frame is to be inserted, its end is thrust through opening a, whereupon said end of the frame engages with bend d' and presses switch spring D away from contact e, as shown in full lines in Fig. 2, whereby the circuit is broken and the light is extin-

guished when the frame is positioned for insertion into the casing. The printing frame is now shoved into position, the lamp being extinguished during such operation, and the engagement of bend d' with the edge of the printing frame holding the switch spring in a non-operative position. When the printing frame is fully inserted into the printing chamber, notch c comes opposite to the bend of the switch spring, the inherent elasticity of which operates to return the switch spring to a normal position, whereby the circuit is closed by the switch spring engaging with contact e, the bend d' of said switch spring fitting into notch c of the printing frame. The lamp thus operates to illuminate the printing chamber, for the purpose of securing photographic print of the negative contained in the frame, all parts of the negative and the sensitized paper being equally exposed to the light of the lamp. After a suitable exposure of the photographic print, the operator withdraws frame C from printing chamber A'. At the beginning of the operation of withdrawing the printing frame, notch c is moved away from the bend d' in the switch spring, and said bend engages with the edge of the printing frame, as a result of which the switch D is moved away from contact e, for the purpose of breaking the circuit and extinguishing the lamp. During the operation of withdrawing the printing frame, the circuit remains open and the lamp is extinguished, but just as the frame leaves the chamber, the bend d' of the switch spring clears the end portion of the printing frame, whereupon the spring D again engages with contact e, for the purpose of closing the circuit and lighting the lamp to illuminate the chamber.

The switch mechanism illustrated in Fig. 4 is similar to the embodiment of the invention shown in Fig. 2, but in lieu of the notch c in the printing frame C, the printing frame C' of Fig. 4 is provided with a contact c'. This contact is positioned on printing frame C', so as to span the space between contact e and the bend d' of switch spring D, when the printing frame is in a position fully inserted within the printing chamber. In this form of switch mechanism the circuit is closed when the printing frame is not in position, and, accordingly, the lamp is lighted and the chamber illuminated. Upon placing the printing frame in position for inserting it through openings a of the casing, the end portion of the frame engages with bend d', so as to move the switch to an open position. The frame is now inserted, the lamp being extinguished during such operation, but when the printing frame reaches its full inserted position, the bend d' of the spring is still in engagement with the frame so that the end of spring D will not

make contact *e*, but at this time the frame contact *c'* makes electrical contact with circuit contact *e* and bend *d'* of the switch, thus completing the circuit and admitting current to the lamp for illuminating the printing chamber. At the beginning of the operation of withdrawing the printing frame from the casing, frame contact *c'* is moved away from bend *d'* and circuit contact *e*, but the switch spring does not return to its normal position, for the reason that bend *d'* thereof remains in engagement with the edge of the frame until said frame shall have been withdrawn a sufficient distance for said bend *d'* to clear the end of the frame, whereupon the switch returns automatically to a closed position, for the purpose of again admitting current to the lamp.

In Fig. 5 of the drawings there is shown a double switch mechanism adapted for use in connection with an ordinary printing frame *C²*, the latter being minus either the notch *c* of Fig. 2, or the frame contact *c'* of Fig. 4. One element of the double switch mechanism is a switch spring *F* positioned near the entrance to the printing chamber, and a second element of the switch mechanism is a switch spring *F'* positioned adjacent to that end of the printing chamber which is to be occupied by an end portion of printing frame *C²* when said frame is fully inserted into the chamber or casing *A*. Spring switch *F* is similar to the spring switches disclosed in Figs. 2 and 4, that is to say, one end of switch *F* is fastened at *g* to insulation *G*; the free end of the spring is provided with the bend *g'*, and the extremity of the spring is adapted for engagement with a contact *h*, the latter being attached at *h'* to insulation *G*. The other switch spring *F'* is fastened at *i* to insulation *I*. The electrical connections for the double switch mechanism are as follows: Feed wire *j* runs directly to the filament of incandescent lamp *B'*. The return wire *j'* is connected at *i* to switch spring *F'*; from contact *I'* extends a conductor *k* which is attached to contact *h*; from the fixed point *j* of switch spring *F* leads a conductor *k²* which is branched on to the return wire *j'*, and from the lamp filament leads a conductor *k²* which is branched on to the conductor *k* between contact *I'* and contact *h*.

The operation of the device thus described, and shown in Fig. 5, is as follows:—When printing frame *C²* is not in the printing chamber, switch *F* is closed and switch *F'* is open, whereupon current flows through feed wire *j* to the filament of the lamp *B'*, through conductor *k²* to contact *h*, switch spring *F* and conductor *k³*, thence to return wire *j'*, said conductor *k³* being attached at one end to the fixed point *g* of switch spring *F*, and at its other end to said return wire *j'*. Current thus flows through the switch *F*

and lamp *B'*, for the purpose of lighting the lamp and illuminating the printing chamber. The sensitized paper and negative having been positioned within the printing frame, and said frame placed in a position to enter opening *a* in the casing *A*, the forward end of the printing frame engages with bend *g'* of switch *F*, thereby pressing said switch *F* away from contact *h*, and breaking the circuit, the result of which is to extinguish the lamp *B'* during the operation of inserting the printing frame into the printing chamber. As soon as the printing frame is fully inserted into chamber, the forward end of said printing frame engages with the free end of switch spring *F'*, pressing the bend *i'* of said spring into engagement with contact *I'*, whereupon the current flows as follows:—through feed wire *j* to the lamp filament, conductor *k²* through conductor *k* to contact *I'*, switch spring *F'* and through return wire *j'*. The lamp is thus lighted and illuminates the chamber so that the light is utilized in securing the desired print through the negative upon the sensitized paper held within frame *C²*. When the work of printing the sensitized paper shall have been completed, the operator removes the frame from casing *A*. As the frame begins to move, switch spring *F'* is released, and the circuit through the lamp is broken, thereby extinguishing the light. The light is out of service during the operation of withdrawing the frame from the casing, but as soon as the frame clears the bend *g'* of switch spring *F*, said spring returns to its normal closed position, and engages contact *h*, whereupon the current is directed through the lamp, and the latter is lighted for illuminating the chamber.

In the practical form of casing *A*, shown in Figs. 1, 2 and 3, it is preferred to construct the casing in knock-down form, whereby all the parts are foldable within a small space. The casing is shown as consisting of a base *A²*, side panels *H*, *H'*, an end panel *J*, an end frame *K*, and a top *L*. Said panels *H*, *H'* are hinged at their lower ends, as at *m* to the base *A²*, whereby one panel, as *H'*, may be folded within said base, and thereafter panel *H* may be folded upon panel *H'*. The socket fixture *B'* is attached to the panel *H'* so as to be foldable therewith, although lamp *B* should be unscrewed from the socket prior to folding the panels within the base. At their upper ends, the panels *H*, *H'* are provided with guide flanges *n*, with which are adapted to interlock other flanges *o* provided on the edge portions of top *L*, whereby the top *L* is adapted to be supported in position by said panels *H*, *H'*, and said top co-operates with said side panels to retain them in their unfolded operative positions. The side panels *H*, *H'* are pro-

vided with longitudinal grooved beads p near their respective edges, as shown in Fig. 2, and with the grooves of said beads interlock the ribs q on flanges q' provided on the end panel J and the frame K . As shown in Fig. 2, end panel J is provided at its side edges with flanges q' , and these flanges are formed with ribs q , whereby the panel J may be slid into position for the flanges q' to overlap the side panels H , H' , and for the ribs q to enter the grooves of beads p , thus locking end panel J to side panels H , H' . In a similar manner frame K is provided at its respective side edges with flanges q' , and these flanges are provided with ribs q , so that frame K may be slid into position for the flanges q' to overlap side panels H , H' , whereupon the ribs q will slide into the grooves of beads p , thus locking frame K to the side panels. The several panels and the top are thus separably connected together in a way to retain themselves in position, and to provide for ready disengagement so that the panels can be folded into the base A^2 , but when the parts are adjusted into their operative positions, the panels and the top are locked together by light-tight joints. Frame K serves the purpose, mainly, of an end panel, similar to panel J , but said frame K is provided with a pane or light of colored glass O , preferably a ruby glass, which is held detachably in position by suitable guideways s attached to the outside of frame K , as shown in Figs. 2 and 3. The printing device is adapted to serve the purposes of a ruby light in a darkened room, for the reason that the rays of light from lamp B are adapted to pass through the colored glass O , and to be so modified that the light will not injuriously effect the sensitized paper which is used in the printing operations. It will be understood, accordingly, that the apparatus of this invention may be used in a manner to illuminate the room in which the printing operation is carried on, thereby affording sufficient light for the operator to change the negatives and the printing paper in the printing frames without injury to the sensitized paper, and to insert and remove the frame, the ruby light affording sufficient illumination to carry on these operations with ease and facility.

Having thus fully described the invention, what I claim as new, and desire to secure by Letters Patent is:—

1. In a photographic printing device, the combination of a printing chamber one wall of which is composed of translucent material, illuminating means positioned within said chamber, and means operable by a printing frame for extinguishing said illuminating means during the acts of inserting and withdrawing said printing frame, said illuminating means being lighted when the

printing frame is wholly withdrawn from the printing chamber, whereby a room or apartment is adapted to be illuminated by rays of light from the illuminating means passing through the translucent material. 70

2. In a photographic printing device, the combination of a printing chamber one wall of which is composed of a colored glass, or the like, a single source of light positioned within said chamber, and a controller operable by a printing frame for extinguishing the single source of light during the acts of inserting and withdrawing the printing frame, said controller operating to maintain the source of light in service after the printing frame is withdrawn from said chamber and also during the period that said printing frame is at rest within the said chamber, whereby upon removal of the printing frame the source of light will illuminate a 85 room or apartment by the rays of light passing through the colored glass.

3. In a photographic printing device, the combination of a printing chamber one of the walls of which is provided with a printing frame slot the area of which slightly exceeds the cross sectional area of the printing frame adapted to be moved therethrough, illuminating means positioned within said chamber, a printing frame insertible and withdrawable through said slot, and a controller co-operating with said printing frame for extinguishing said illuminating means during the acts of inserting and withdrawing the printing frame, said controller acting 100 to maintain the illuminating means in service when the printing frame is withdrawn and also during the period that the printing frame is at rest within said chamber.

4. In a photographic printing device, the combination of a printing chamber one of the walls of which is composed of a colored glass, a source of light positioned within said chamber, a printing frame insertible into and withdrawable from said chamber, and a controller switch separated from the printing frame and positioned within said chamber in the path of said printing frame, said controller switch co-operating with a member for maintaining the source of light 110 in service when the printing frame is removed from said chamber and also during the period that said printing frame is at rest therein, said controller switch operating to extinguish the source of light during the 120 acts of inserting and withdrawing the printing frame.

5. In a photographic printing device, the combination of a printing chamber one wall of which is composed of a colored glass, a 125 source of light positioned within said chamber, a controller positioned within said chamber and connected with said source of light, and a printing frame insertible into and withdrawable from said printing chamber,

- 5 said controller and the printing frame co-operating with each other to extinguish the light during the operations of inserting and withdrawing the printing frame, and said controller acting independently of the printing frame when the latter is withdrawn for maintaining the source of light in service.
6. In a photographic printing device, a printing chamber, an incandescent electric lamp therein, and a switch mechanism included in circuit with said lamp and positioned in the path of a printing frame, said switch mechanism being operable by the printing frame so that the light is extinguished on starting to introduce the printing frame into said chamber and illuminated upon the complete introduction of the printing frame within the chamber.
7. In a photographic printing device, a printing chamber, an incandescent electric lamp therein, and a switch mechanism included in circuit with said lamp and positioned in the path of a plate holder, said switch mechanism being operable by the plate holder so that the light is extinguished on starting to introduce the plate holder into said chamber and illuminated upon the complete introduction of the plate holder within the chamber, said switch mechanism being operated, also, by the plate holder to extinguish the light upon starting to withdraw the plate holder from the chamber and to illuminate the lamp upon the complete withdrawal of said plate holder from the chamber.
8. In a photographic printing device, a casing provided with an opening, means for illuminating said casing, switch mechanism for controlling said illuminating means, and a printing frame insertible and withdrawable through said opening, said printing frame operating the switch mechanism to extinguish the light during such insertion and withdrawal, said frame having means whereby the switch mechanism operates to light the illuminating means, when said frame is in operative position within the casing.
9. In a photographic printing device, a casing provided in its lower part with an opening or slot the width of which slightly exceeds the cross sectional dimensions of a printing frame, means positioned within the upper part of said casing for illuminating the same, and switch mechanism positioned in the path of a printing frame for operation thereby, said switch mechanism controlling said illuminating means independently of the printing frame whereby the illuminating means is maintained in service upon the withdrawal of the printing frame from the printing chamber and during the period that said printing frame is at rest within said printing chamber, said switch mechanism operating also to extinguish the illuminating means during the operations of inserting and withdrawing the printing frame.
10. In a photographic printing device, a casing embodying a base section and a plurality of upper panels foldable relatively to the base section, said base section being provided with an opening for the introduction and withdrawal of a plate holder, combined with means for illuminating the casing, and a switch mechanism for controlling said illuminating means.
11. In a photographic printing device, a casing provided with a colored transparent pane, illuminating means positioned within said casing, and means operable by the insertion and withdrawal of a printing frame for controlling said illuminating means, said means operating to maintain the illuminating means in service upon the withdrawal of the printing frame from the casing.
- In testimony whereof I have signed my name to this specification in the presence of two subscribing witnesses.
